(57) **CLAIM**

The ornamental design for a LED light, as shown and described.

DESCRIPTION

FIG. 1 is a front, right and top perspective view of a LED light, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, right and top perspective view of a second embodiment of the LED light of FIG. 1.

FIG. 11 is a front, right and top perspective view of a third embodiment of the LED light of FIG. 1.

FIG. 12 is a perspective view of the LED light of FIG. 10 in another state; and,

FIG. 13 is a perspective view of the LED light of FIG. 11 in another state.

The broken lines depict portions of the LED light that form no part of the claimed design. The dot-dash broken lines in FIGS. 1 and 9 depict the boundaries of the enlargements that form no part of the claimed design.
